UNITED STATES PATENT OFFICE

JAMES F. MCINTIRE, OF DETROIT, MICHIGAN, ASSIGNOR TO UNITED STATES RADIATOR CORPORATION, OF DETROIT, MICHIGAN, A CORPORATION OF NEW YORK

RADIATOR CONSTRUCTION

Original application filed March 12, 1932, Serial No. 598,355. Divided and this application filed August 15, 1932. Serial No. 628,949.

This invention relates generally to radiators and constitutes a division of my application filed March 12, 1932, bearing Serial No. 598,355.

5 In the accompanying drawing:

Figure 1 is a top plan view of a portion of a radiator embodying my invention;

Figure 2 is a sectional view taken on the line 2—2 of Figure 1;

10 Figure 3 is a sectional view taken on the line 3—3 of Figure 1;

Figure 4 is a side elevation of the construction illustrated in Fig. 1;

15 Figure 5 is a sectional view taken on the line 5—5 of Figure 4;

Figure 6 is a side elevation of the radiator on a reduced scale.

Referring now to the drawing, A and B respectively are the end walls; C and D respectively are the side walls; E and F respectively are the headers; G is the steam or water-way; H and I respectively are the fins; and J and K respectively are the partitions of a radiator embodying my invention.

20 As shown, the parts just mentioned are integrally united and form a radiator that has a uniform cross sectional area throughout its length. Preferably the end walls A and B are flat and are relatively thick. The side walls C and D are thinner than the end walls and are terminally secured thereto at the outer upright edges thereof. The headers E and F are substantially rectangular in shape and are vertically disposed upon the inner sides of the end walls A and B in spaced relation to the side walls C and D. Preferably threaded openings 1 and 2 respectively are provided in the end walls A and B and

25 headers E and F for the reception of suitable piping (not shown). The steam or water-way G is located between the side walls C and D in substantially parallel relation thereto and is terminally connected to the headers E and F. Preferably this water-way G is

30 centered relative to the side walls C and D and are vertically disposed upon the inner sides of the end walls A and B in spaced relation to the side walls C and D. Preferably threaded openings 1 and 2 respectively are provided in the end walls A and B and

35 headers E and F for the reception of suitable piping (not shown). The steam or water-way G is located between the side walls C and D in substantially parallel relation thereto and is terminally connected to the headers E and F. Preferably this water-way G is

40 centered relative to the side walls C and D and are vertically disposed upon the inner sides of the end walls A and B in spaced relation to the side walls C and D. Preferably threaded openings 1 and 2 respectively are provided in the end walls A and B and

45 headers E and F for the reception of suitable piping (not shown). The steam or water-way G is located between the side walls C and D in substantially parallel relation thereto and is terminally connected to the headers E and F. Preferably this water-way G is

and opens into the headers E and F. The top and bottom walls 4 and 5 respectively of said water-way are substantially Y-shaped in cross section while the opposite side walls 6 and 7 respectively thereof are parallel and 50 extend between the furcations 8 and 8' of the Y's. The partitions J and K respectively are upon opposite sides of the water-way and are terminally secured to the headers E and F. Preferably these partitions are substantially 55 midway between and are parallel to the water-way G and side walls C and D. Moreover, both the partitions J and K and the side walls C and D are provided throughout their length at points substantially mid- 60 way of their upper and lower edges with longitudinally extending slots 9 and 10 respectively. The fins H are located between the headers E and F and project laterally from opposite sides 6 and 7 of the water- 65 way to the partitions J and K, while the fins I are located between the end walls A and B and project laterally from the partitions J and K and headers E and F to the side walls C and D. Preferably the fins H 70 and I are relatively thin and are closely spaced in parallel relation to the end walls A and B. In this connection it will be noted that the upper edges of the end walls A and B, side walls C and D, partitions J and K, 75 water-way G and fins H and I are substantially flush and that the lower edges of said parts are also substantially flush. The upper ends of the headers E and F are just below the upper edges of the fins I and have ribs 80 11 thereon in line with and forming continuations of the upper edges 4' of the water-way.

Thus from the foregoing description it will 85 be readily apparent that I have provided an extremely efficient and practical radiator wherein the maximum of heat radiation is provided. The heat from the water-way G and headers E and F will be transferred by the fins H and I and partitions J and K to the 90

air flowing upwardly through the radiator with the result that such air will be effectively and thoroughly heated. In this connection it will be noted that any suitable means such as four legs (not shown) may be utilized for supporting the radiator when in use. Moreover, such a radiator may be readily installed either within or upon the outer side of a wall and may be concealed or covered by any suitable means which will provide for the circulation of cold air below and of the heated air above the radiator. One form of enclosure is illustrated in my application filed July 30, 1932, bearing Serial No. 626,526.

15. What I claim as my invention is:

1. A radiator having end and side walls, headers upon the inner sides of said end walls, a steam or water-way extending between the side walls and terminally connected to the headers, fins projecting from opposite sides of the water-way and headers to the side walls, and partitions between the fins substantially midway between the side walls and water-way and substantially parallel thereto.

2. A radiator having end and side walls, having a substantially rectangular enclosure, headers within the enclosure upon the inner sides of said end walls, and a steam or water-way extending between and terminally connected to the headers, the upper and lower longitudinal edges of the water-way being substantially V-shape in cross section and being substantially flush with the upper and lower ends of the headers.

3. A radiator having end and side walls secured together and forming a substantially rectangular enclosure, headers within the enclosure upon the inner sides of said end walls, and a steam or water-way extending between and terminally connected to the headers, the upper and lower longitudinal edges of the water-way being substantially V-shape in cross section, and opposite sides of the water-way being parallel to each other and to the side walls of the enclosure and extending between and merging into the sides of the V's.

4. A radiator casting of uniform cross sectional area throughout its length having end and side walls secured together and forming a substantially rectangular enclosure, headers within the enclosure upon the inner sides of said end walls, a water-way extending between and terminally connected to the headers, the depth of the water-way being substantially equal to the height of said enclosure, and fins projecting from the headers and water-way to the side walls with their upper and lower edges substantially flush with the upper and lower edges of the side and end walls and in parallel relation to the latter whereby the fins and walls provide substantially flat gratings at the top

and bottom of the casting from one end thereof to the other.

5. A radiator having end and side walls, headers upon the inner sides of said end walls, a water-way extending between and terminally secured to said headers, the top and bottom walls of said water-way being substantially flush with the upper and lower edges of said end walls, and ribs upon the upper and lower ends of said headers between said end walls and water-way and forming extensions of the top and bottom walls of said water-way.

6. A radiator having end and side walls, headers upon the inner sides of said end walls, and partitions extending between and terminally secured to said headers.

7. A radiator having end and side walls, headers upon the inner sides of said end walls, a water-way extending between and terminally secured to said headers, and partitions upon opposite sides of said water-way and extending between and terminally secured to said headers.

8. A radiator having end and side walls secured together, headers upon the inner sides of said end walls, partitions extending between and terminally secured to said headers, said partitions being substantially parallel to said side walls, and a water-way extending between and terminally secured to said headers, opposite sides of said water-way being substantially parallel to said partitions.

9. A radiator having end and side walls secured together, headers upon the inner sides of said end walls, partitions extending between and terminally secured to said headers, said partitions and side walls being substantially parallel and provided substantially midway of their upper and lower edges with longitudinally extending slots.

10. A radiator having end walls and side walls secured to said end walls at the outer upright edges thereof, headers upon the inner side of said end walls in spaced relation to said side walls, partitions extending between and secured to said headers, a water-way extending between the partitions and secured to said headers, fins projecting laterally from the water-way to the partitions, and fins projecting laterally from the partitions and headers to the side walls.

11. A radiator having end walls and side walls secured to said end walls at the outer upright edges thereof, headers upon the inner side of said end walls in spaced relation to said side walls, partitions extending between and secured to said headers, and a water-way extending between the partitions and secured to said headers, fins projecting laterally from the waterway to the partitions, said partitions and side walls being substantially parallel and provided throughout their length with longitudinally extending slots.

12. A radiator having end and side walls forming a substantially rectangular enclosure, headers within the enclosure upon the inner sides of said end walls, a steam or water-way extending between and terminally connected to the headers, said water-way being substantially midway between and parallel to said side walls, the height of the water-way and end and side walls being substantially uniform, and partitions extending between and terminally connected to said headers, said partitions being substantially midway between and parallel to said water-way and side walls.

15 13. A radiator casting having upright substantially parallel side walls, upright end walls extending between and forming with said side walls a substantially rectangular enclosure, an elongated fluid-way extending between and terminally connected to the end walls and having a fluid inlet and outlet, said fluid-way being substantially midway between the side walls and substantially equal in depth to the height of the said side walls, 25 the width of the fluid-way being less than one-half the height thereof, and means within the enclosure for dissipating heat from the fluid-way and directing the passage of air within the enclosure including partitions upon opposite sides and substantially parallel 30 to said fluid-way.

14. A radiator casting having upright substantially parallel side walls, upright end walls extending between and forming with said side walls a substantially rectangular enclosure, an elongated fluid-way extending between and terminally connected to the end walls, the depth of said fluid-way being substantially equal to the height of said enclosure, the width of said fluid-way being materially less than the depth thereof, partitions within the enclosure upon opposite sides of the fluid-way, and fins extending between the fluid-way and partitions and between the latter and side walls of the enclosure, the height of said partition and fins being substantially equal to the height of said fluid-way and enclosure.

15. A radiator having substantially parallel elongated side walls, headers between said side walls at opposite ends thereof, substantially parallel partitions between said side walls and terminally connected to said headers, a fluidway between said partitions and terminally connected to said headers, and connections between said walls, partitions, and headers including fins projecting laterally from opposite sides of said fluidway to said partitions, and fins projecting from the outer sides of said partitions and said headers to said side walls.

16. A radiator having substantially parallel elongated side walls, headers at opposite ends of said side walls and provided 35 with fluid openings, substantially parallel

partitions between said side walls and terminally secured to said headers, a fluidway between said partitions and terminally connected to said headers, and connections between said walls, partitions and fluidway including substantially parallel fins projecting laterally from opposite sides of said fluidway to said partitions, and fins projecting laterally from the outer sides of said partitions to said side walls.

In testimony whereof I affix my signature.
JAMES F. MCINTIRE.
